Primary Examiner — Brett Miller*Assistant Examiner* — Nader Abadir(74) *Attorney, Agent, or Firm* — Vladimir Postnikov(57) **CLAIM**

The ornamental design for a mixing cup, as shown and described.

DESCRIPTION

FIG. 1 is a front elevation view of a mixing cup showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

1 Claim, 8 Drawing Sheets
